DECORATIVE STITCH ATTACHMENTS

Carl G. Baehr, West Haven, Conn., assignor to The Greist Manufacturing Company, New Haven, Conn., a corporation of Connecticut

Application January 13, 1956, Serial No. 559,007

16 Claims. (Cl. 112—160)

This invention relates to sewing machine attachments, and more particularly to an attachment for effecting decorative stitches in various patterns.

In machines of this character it is usual to provide a frame portion attachable to the presser foot of a sewing machine, the frame carrying the mechanism of the attachment, which mechanism is operated by a fork arm actuated by the needle bar. Such decorative stitch attachments usually are provided with means for moving the cloth laterally of the line of feed of the sewing machine so as to provide zigzag stitches in various patterns. It is also desirable in such machines to be able to effect a certain number of stitches in a line and then move the cloth laterally and effect a given number of stitches in a line parallel to, but displaced laterally from, the first series of stitches. One of the features of the present invention is to provide readily adjustable mechanism for producing decorative stitches of various patterns, the mechanism for changing from one pattern to another being accessible to the operator and readily manipulated without disconnecting the attachment from the machine.

As illustrated a presser foot is carried by a lever pivotally attached to the frame of the machine, and this lever is oscillated by means of a cam having an internal cam track of sinuous form within which is received a pin or cam follower secured to the lever. The cam member is actuated by a fork arm mounted to oscillate on the frame and also actuated by the fork arm in a step-by-step movement is a bank of cams, the cams being formed or cut differently so that each one will effect a different stitch pattern.

These cams are adapted through a train of mechanism to permit or prevent actuation of the internal cam member previously referred to by the fork arm so that the particular type of stitch effected by the attachment is determined by the particular cam which is placed in operation.

A cam follower is provided which is movable axially of the bank of cams so as to place the follower in engagement with the periphery of a selected one of the cams so as to select any desired one of the cams and thereby determine the stitch pattern.

One object of the present invention is to provide a decorative stitch attachment for sewing machines of improved form and one which is readily manipulated and adjusted.

A further object of the invention is to provide a decorative stitch attachment for sewing machines which is capable of effecting a large number of stitch patterns and which may be set or adjusted to effect any selected one of a number of patterns.

Still another object of the invention is to provide a decorative stitch attachment having a presser foot carried by a lever pivotally secured to the frame of the attachment, this lever being actuated by the usual fork arm, and to provide a bank of cams which may be selectively employed to either permit or prevent actuation of the lever upon any given stroke of the fork arm so as to

effect a variety of stitch patterns depending upon the particular cam employed.

To these and other ends the invention consists in the novel features and combinations of parts to be herein-after described and claimed.

In the accompanying drawings:

Fig. 1 is a side elevational view of a sewing machine attachment embodying my invention;

Fig. 2 is a side elevational view showing the opposite side of the attachment;

Fig. 3 is a top plan view;

Fig. 4 is a bottom plan view;

Fig. 5 is an end elevational view of the attachment;

Fig. 6 is a sectional view on line 6—6 of Fig. 1;

Fig. 7 is a partial sectional view on line 7—7 of Fig. 5;

Fig. 8 is a view similar to Fig. 1, some parts being omitted and showing the parts in a position different from that shown in Fig. 1;

Fig. 9 is a sectional view on line 9—9 of Fig. 1;

Fig. 10 is a view similar to Fig. 9 but showing the parts in another position;

Fig. 11 is a detail perspective view of the cam follower and its adjusting mechanism;

Fig. 12 illustrates three of the controlling cams employed; and

Fig. 13 is a perspective view of the controlling lever which is actuated by the cam follower.

As illustrated in the drawings, the attachment comprises a main frame member 10 of substantially U-shaped form to which is secured an auxiliary frame member 11 (Fig. 5) which is also of U-shaped form in cross section. Pivoted secured to the frame member 10 is a lever 12 carrying at its forward end a presser foot 13 which is adapted to engage the cloth and feed the same laterally when the lever is oscillated.

As shown, the lever 12 is pivoted upon a pin 14, which pin is adjustable in a slot 15 in the lever 12 and in a registering slot 16 (Fig. 3) in the base of the frame 10. The pivot pin 14 is secured to an arm 18 of a slide member 19 shown in dotted lines in Fig. 4, which slide member is provided with a slot 20 to receive a pin 21 secured in the base of the frame member 11 so that the slide may be guided in its movements. The slide is also provided

with a vertically turned edge portion 22 provided with a slot 23 (Fig. 2) and an adjusting screw 24 passes through the slot 23 (Fig. 6) in order to frictionally secure the slide in any adjusted position. As will be obvious, adjustment of the slide and the consequent adjustment of the pivot pin 14 will adjust the throw of the lever 12. Secured to the lever 12 adjacent the rear end thereof is a cam follower 25 (Figs. 1 and 2), which follower is received in a sinuous or wavy internal cam track 26 of a cam member 27 rotatably mounted in the upper standing leg portions 28 and 29 of the frame 10. This cam is secured to a shaft 30 and may be manually rotated when desired by the knob 31.

The usual fork arm 32 is pivotally mounted upon a shaft 33 so that it may be oscillated about the shaft. Secured to this shaft is a ratchet 34, the teeth of which are engaged by a pawl 35 pivoted at 36 to the fork arm 32, the pawl being urged into engagement with the teeth of the ratchet wheel by a spring 37 so that oscillation of the fork arm will effect step-by-step movement of the ratchet wheel and the shaft 33.

Pivoted at 38 to the fork arm 32, which pivot point is eccentric to the pivot of the fork arm, is a link 39, which link extends rearwardly and is connected at its rear end at 40 to an ear 41 of a lever 42 oscillatably mounted on the axis of the shaft 30. Pivoted mounted on the lever 42 is a pawl 43 urged by a spring 44 into engagement with

the teeth of a ratchet wheel 45 secured to the shaft 30 of the internal cam 27.

With the construction so far described, it will be obvious that when the fork arm is oscillated, the shaft 33 will be rotated in a step-by-step movement and through the link 39, lever 42, pawl 43 and ratchet wheel 45 the cam member 27 will also be rotated in a step-by-step movement. This would effect a zigzag or lateral stitch at each down stroke of the needle bar. However, means are provided as will be hereinafter described to hold the pawl 43 from engagement with the ratchet 45 when desired so that straight stitching may be effected in any desired pattern between zigzag or lateral stitching. Also, as will be described, means are provided to continuously hold the pawl 43 from engagement with the teeth of the ratchet wheel so as to produce straight stitching, if desired. This means will now be described.

Pivoted upon the frame member 28 at 47 (Fig. 8) is a lever 48 shown more particularly in Fig. 13. This lever is of curved form and is provided with an upstanding L-shaped arm 49 which projects upwardly below a pin or knob 50 secured to the pawl 43. When the lever 48 is in the position shown in Fig. 1, it is out of engagement with the pin 50, as shown in Fig. 9, and, therefore, will permit the free end of the pawl member 43 to engage the ratchet wheel 45. When, however, the lever 48 is in the position shown in Fig. 8, the arm 49 will engage the pin 50 and raise the pawl 43 from engagement with the teeth of the ratchet 45, as shown in Fig. 10 of the drawings.

The lever 48 is provided with a pin 52 which projects through an elongated opening 53 in the frame member 28 and which is received in an elongated opening 54 in a cam follower 55 having a rounded end follower portion 56 to engage the selecting cams as will be hereinafter described. The follower 55 is also provided with an opening 57 receiving a pin 58 secured to the frame member 10 and projecting into the frame member 11 (Fig. 3) so that the follower is pivoted for rocking movement upon this pin. With this arrangement it will be seen that as the follower is rocked about its pivot, it will swing the lever 48 about its pivot 47 due to the engagement of the pin 52 in the elongated opening 54.

The follower 55 is provided with a bridge member 59, one end of which is secured to the follower and the other end of which is provided with a downwardly projecting ear 60 having an opening 61 which also loosely but snugly receives the pin 58. Projecting laterally from the ear 60 is a lug 62 having a headed pin 63 secured thereto and upstanding therefrom. This pin is received in an opening 64 (Fig. 2) in a Z-shaped lever 65. This lever is pivoted upon a pin 66 secured to a member 67 of the frame 11 and urged downwardly against the member 67 (Figs. 5 and 6) by a spring 68. The other end of the lever 65 is provided with an adjusting button 70 and is also provided with a downwardly projecting tooth 71 (Fig. 6) adapted to be received in any one of a plurality of openings 72 in a member 73 likewise secured to the frame 11.

It will be seen that as the cam follower structure, shown in Fig. 11, is secured to the lever 65 by the headed pin 63, adjustment of this lever about its pivot 66 will move the follower structure laterally of the frame member 11.

Secured to the shaft 33 which carries the ratchet 34 and fork arm 32 are a plurality of cams 75, 76 and 77 (Figs. 3 and 12) and also a cylindrical member 78. These are the selecting cams which serve to select the particular pattern which it is desired to make, and it will be noted that the cam 75 is provided with two notches or indentations 75^a, while the cam 76 is provided with four notches or recesses 76^a, and the cam 77 provided at diametrically opposite portions with two adjacent recesses or notches 77^a. It will be, of course, understood that any arrangement of recesses or notches desired may be provided upon these selecting cams to effect any desired type of stitch. The member 78 has a smooth periphery and when the cam follower is moved to a position where

it engages this member (which is smaller in diameter than the cam members 75, 76 and 77), there will be no movement imparted to the follower.

The lever 65 is also provided with a downwardly depending arm 80 (Fig. 5) provided with an opening 81 which loosely receives a rod 82 secured to the lever 48 (Fig. 13), which rod passes loosely through openings 83 in the upstanding walls 28 and 29 of the frame member 10. Therefore, when the free end of the lever 65 is raised by the adjusting button 70, the rod 82 will also be raised, swinging the lever 48 about its pivot 47. This will effect movement of the pin 52 about the pivot point 47 and thus raise the free end of the follower 55 due to the engagement of the pin 52 in the opening 54 of the follower 55 and move the end portion 56 downwardly away from the selecting cams, as shown in Fig. 8.

It will be appreciated that if it were attempted to shift the follower 55 laterally while the end portion 56 was engaged in one of the notches 75^a, 76^a or 77^a, of one of the cams, such movement would be prevented by engagement of the portion 56 with the side of an adjacent cam. Therefore, whenever the lever 65 is raised by the adjusting button 70 to withdraw the downwardly projecting tooth 71 from one of the notches 72 in order to shift the follower laterally, the cam follower portion 56 will be withdrawn downwardly from the periphery of the cam with which it is engaged to permit such movement.

The operation of the device may now be briefly described. Suppose, for example, that the end 56 of the cam follower 55 is in engagement with the selecting cam 76, as shown in Fig. 3. This cam, as will be obvious, is provided with four peripheral recesses or notches 76^a, and the ratchet wheel 34 is provided with twelve teeth. Therefore, at every third stitch the end portion 56 of the follower will fall into one of the recesses 76^a while during the two intervening stitches the follower will ride upon the cylindrical surfaces of the cam which are, of course, of greater distance from the axis than the bottom of the recesses. When the follower drops into one of the recesses, the follower will be permitted to swing through a small arc in a clockwise direction about the pivot pin 58 and, by the engagement of the opening 54 in the follower with the pin 52 on the lever 48, will permit this lever to swing in a clockwise direction about its pivot 47 and thereby permitting the arm 49 to move downwardly, as shown in Fig. 8, thus permitting the spring 44 to urge the pawl 43 into engagement with the ratchet 45 and impart a one-step movement to the sinuous cam member 27. This will effect lateral movement of the lever 12 about its pivot pin 14 and thus will effect a stitch laterally of the line of stitches previously made.

Upon continued operation of the needle bar, the selecting cam 76 will be moved through a one-step movement by the pawl 35 on the fork arm 32 and the follower portion 56 will ride up upon the circular peripheral portion of the cam, thus moving the follower 55 in a counterclockwise direction about its pivot and likewise moving the lever 48 in the same direction due again to the engagement of the pin 52 in the opening 54. This will raise the arm 49 of the lever 48 and move the pawl 43 upwardly so that it will no longer engage the ratchet 45 and thus the cam member 27 will remain stationary. Thus straight stitching will be made for two strokes of the needle bar until the follower portion 56 of the follower 55 engages the next recess 76^a in the selecting cam 76 when the cloth will be moved laterally in the opposite direction, and the following two stitches will be made in a line spaced laterally from those previously made.

It will be apparent that as the cam 76 contains four recesses 76^a, it will make three stitches in a line, and then the material will be shifted and the three following stitches will be made in another line spaced from and parallel to the first. In other words, the use of this cam will result in two parallel lines, each containing sets

or groups of three stitches. If the cam 75 is employed, the same result will be obtained except that the two lines of stitching will consist of groups of six stitches. If cam 77 is employed, the result will be a group of five stitches in a line and then an offset stitch, following which there will be another group of five stitches in the same line as the first.

If the cam follower 55 is moved into engagement with the cylindrical member 78 which is of smaller diameter than the selecting cams 75, 76 and 77, the arm 49 of the lever 48 will remain in its lower position, and the pawl 43 will be always in engagement with the teeth of the ratchet 45 so that a lateral stitch will be made at each stroke of the needle bar, thus making a continuous zigzag stitch.

As previously described, the follower member 55 is moved laterally to engage a selected one of the cam members or the member 78 by movement of the lever 65 to which the follower is connected by the pin 63. When it is desired to shift the follower from one cam to another, the adjusting button 70 is raised to release the tooth 71 from one of the openings 72 which permits shifting of the lever 65. As also previously explained, raising of the free end of the lever 65 also, by means of the connection of the depending arm 80 with the rod 82 and the connection of the lever 48 with the follower by means of the pin 52, will swing the follower 55 about its pivot so as to disengage the end 56 from the cam with which it has been engaged. When the lever 65 has been shifted to the proper position, the button 70 is released and the tooth 71 will drop into the corresponding opening 72 of the selected cam so as to hold the follower in the proper position.

It is, of course, possible to raise the adjusting button 70 and permit the tooth 71 to remain supported upon the upper surface of the member 73 between two adjacent openings 72. This will hold the end 56 of the follower 55 out of engagement with the cams and thus hold the pawl 43 out of engagement with the ratchet 45 so that the cam member 27 is not rotated and straight stitching will be effected.

The cam follower is urged into engagement with the selecting cam members by the spring 44 which engages the pawl 43. As will be seen from Fig. 10, the pin 50 connected to the pawl bears upon the arm 49 and thus tends to rock the lever 48 in a clockwise direction about its pivot and move the end 56 of the follower toward the selecting cams.

While I have shown and described a preferred embodiment of my invention, it will be understood that it is not to be limited to all of the details shown, but is capable of modification and variation within the spirit of the invention and within the scope of the claims.

What I claim is:

1. A sewing machine attachment comprising a frame, a lever pivoted to the frame for oscillating movement, a presser foot carried by the lever, means to oscillate said lever comprising a rotatable cam member, a fork arm provided to the frame, means connecting said fork arm to the cam member to rotate the same in a step-by-step movement, a second cam member rotatably mounted on the frame and actuated by the fork arm, and a cam follower engaged by said cam and moved thereby to disable said connection.

2. A sewing machine attachment comprising a frame, a lever pivoted to the frame for oscillating movement, a presser foot carried by the lever, means to oscillate said lever comprising a rotatable cam member, a fork arm pivoted to the frame, means connecting said fork arm to the cam member to rotate the same in a step-by-step movement including a ratchet wheel connected to said cam member, and a pawl operated by the fork arm and adapted to engage the ratchet wheel, and means also actuated by the fork arm to disengage the pawl from the ratchet wheel, said last-named means comprising

a second cam rotatably mounted on the frame and actuated by the fork arm, a cam follower engaged by said cam, and means operatively connecting said cam follower to said pawl to disengage the pawl from the ratchet wheel.

3. A sewing machine attachment comprising a frame, a lever pivoted to the frame for oscillating movement, a presser foot carried by the lever, means to oscillate said lever comprising a rotatable cam member, a fork arm pivoted to the frame, means connecting said fork arm to the cam member to rotate the same in a step-by-step movement, and means also actuated by the fork arm to periodically disable said connection, said last-named means comprising a second cam member rotatably mounted on the frame and rotated in a step-by-step movement by oscillation of the fork arm, and a cam follower engaged and actuated by said second cam.

4. A sewing machine attachment comprising a frame, a lever pivoted to the frame for oscillating movement, a presser foot carried by the lever, means to oscillate said lever comprising a rotatable cam member, a fork arm pivoted to the frame, means connecting said fork arm to the cam member to rotate the same in a step-by-step movement, means also actuated by the fork arm to periodically disable said connection, said last-named means comprising a plurality of selecting cam members rotatably mounted on the frame and rotated in a step-by-step movement by oscillation of the fork arm, and a follower adjustable for engagement by a selected one of said cams.

5. A sewing machine attachment comprising a frame, a lever pivoted to the frame for oscillating movement, a presser foot carried by the lever, means to oscillate said lever comprising a fork arm oscillatably mounted on the frame and operatively connected to the lever to oscillate the same, a second cam member rotatably mounted on the frame and actuated by the fork arm, a cam follower engaged by said cam and moved thereby to disable said connection.

6. A sewing machine attachment comprising a frame, a lever pivoted to the frame for oscillating movement, a presser foot carried by the lever, means to oscillate said lever comprising a fork arm oscillatably mounted on the frame and operatively connected to the lever, means movably mounted on the frame and also actuated by the fork arm to intermittently break said connection, said last-named means comprising a plurality of selecting cams rotatably mounted on the frame and rotated in a step-by-step movement by said fork arm, and a follower adjustable for engagement by a selected one of said cams.

7. A sewing machine attachment comprising a frame, a lever pivoted to the frame for oscillating movement, a presser foot carried by the lever, means to oscillate said lever comprising a fork arm oscillatably mounted on the frame, means including a cooperating ratchet wheel and pawl for connecting said fork arm to said lever for actuation of the latter, and means movably mounted on the frame and also actuated by the fork arm for intermittently holding said pawl out of engagement with the ratchet wheel, said last-named means comprising a second cam

rotatably mounted on the frame and actuated by the fork arm, a cam follower engaged by said cam, and means operatively connecting said cam follower to said pawl.

8. A sewing machine attachment comprising a frame, a lever pivoted to the frame for oscillating movement, a presser foot carried by the lever, means to oscillate said lever comprising a fork arm oscillatably mounted on the frame, means including a cooperating ratchet wheel and pawl for connecting said fork arm to said lever for actuation of the latter, means movably mounted on the frame and also actuated by the fork arm for intermittently holding said pawl out of engagement with the ratchet wheel, said last-named means comprising a plurality of selecting cams rotatably mounted on the frame and rotated in a step-by-step movement by said fork arm, and a follower adjustable for engagement by a selected one of said cams.

9. A sewing machine attachment comprising a frame, a lever pivoted to the frame for oscillating movement, a presser foot carried by the lever, means to oscillate said lever comprising a fork arm oscillatably mounted on the frame, means including a cooperating ratchet wheel and pawl for connecting said fork arm to said lever for actuation of the latter, means movably mounted on the frame and also actuated by the fork arm for intermittently holding said pawl out of engagement with the ratchet wheel, said last-named means comprising a plurality of selecting cams mounted on the frame for coaxial rotation and rotated in a step-by-step movement by said fork arm, means for placing a selected one of said cams in operation comprising a cam follower shiftably mounted on the frame for engagement with a predetermined one of said selecting cams, and manually operated means for shifting said cam follower.

10. A sewing machine attachment comprising a frame, a lever pivoted to the frame for oscillating movement, a presser foot carried by the lever, means to oscillate said lever comprising a fork arm oscillatably mounted on the frame, means including a cooperating ratchet wheel and pawl for connecting said fork arm to said lever for actuating the latter, a plurality of selecting cams rotatably mounted on the frame and rotated by said fork arm in a step-by-step movement, means for placing a selected one of said cams in operation, and connecting means between said cams and said pawl for intermittently holding the latter out of engagement with the ratchet wheel, said connecting means including a second lever pivotally mounted on the frame and adapted to engage the pawl, and a cam follower actuated by the cams and connected to said lever for actuating the latter.

11. A sewing machine attachment comprising a frame, a lever pivoted to the frame for oscillating movement, a presser foot carried by the lever, means to oscillate said lever comprising a fork arm oscillatably mounted on the frame, means including a cooperating ratchet wheel and pawl for connecting said fork arm to said lever for actuating the latter, a plurality of selecting cams rotatably mounted on the frame and rotated by said fork arm in a step-by-step movement, means for placing a selected one of said cams in operation, connecting means between said cams and said pawl for intermittently holding the latter out of engagement with the ratchet wheel, said connecting means including a second lever pivotally mounted on the frame and adapted to engage the pawl, a cam follower actuated by the cams and connected to said lever for actuating the latter, and manually operated means for shifting said cam follower into engagement with a selected one of said cams.

12. A sewing machine attachment comprising a frame, a lever pivoted to the frame for oscillating movement, a presser foot carried by the lever, means to oscillate said lever comprising a fork arm oscillatably mounted on the frame, means including a cooperating ratchet wheel and pawl for connecting said fork arm to said lever for actuating the latter, a plurality of selecting cams rotatably mounted on the frame and rotated by said fork arm in a step-by-step movement, means for placing a selected one of said cams in operation, connecting means between said cams and said pawl for intermittently holding the latter out of engagement with the ratchet wheel, said connecting means including a second lever pivotally mounted on the frame and adapted to engage the pawl, a cam follower actuated by the cams and connected to said lever for actuating the latter, manually operated means for shifting said cam follower into engagement with a selected one of said cams, and means for moving said follower out of engagement with the selecting cams when it is shifted by said manually operated means.

13. A sewing machine attachment comprising a frame, a lever pivoted to the frame for oscillating movement, a

5 presser foot carried by the lever, means to oscillate said lever comprising a cooperating pawl and ratchet wheel, a fork arm oscillatably mounted on the frame and connected to said pawl to effect step-by-step rotation of the ratchet wheel, a plurality of selecting cams rotatably mounted on the frame, means for rotating said cams in a step-by-step movement by oscillation of said fork arm, a member movably mounted on the frame and adapted to engage said pawl to hold it out of engagement with the ratchet wheel, a cam follower connected to said member to actuate the same but shiftable relatively thereto, and means for shifting said follower to place it into engagement with a selected one of said selecting cams.

14. A sewing machine attachment comprising a frame, a lever pivoted to the frame for oscillating movement, a presser foot carried by the lever, means to oscillate said lever comprising a cooperating pawl and ratchet wheel, a fork arm oscillatably mounted on the frame and connected to said pawl to effect step-by-step rotation of the ratchet wheel, a plurality of selecting cams rotatably mounted on the frame, means for rotating said cams in a step-by-step movement by oscillation of said fork arm, a member movably mounted on the frame and adapted to engage said pawl to hold it out of engagement with the ratchet wheel, a cam follower connected to said member to actuate the same but shiftable relatively thereto, means for shifting said follower to place it into engagement with a selected one of said selecting cams, said selecting cams being coaxially mounted on the frame, and said follower being shiftable in a direction substantially parallel to said axis.

15. A sewing machine attachment comprising a frame, a lever pivoted to the frame for oscillating movement, a presser foot carried by the lever, means to oscillate said lever comprising a cooperating pawl and ratchet wheel, a fork arm oscillatably mounted on the frame and connected to said pawl to effect step-by-step rotation of the ratchet wheel, a plurality of selecting cams rotatably mounted on the frame, means for rotating said cams in a step-by-step movement by oscillation of said fork arm, a member movably mounted on the frame and adapted to engage said pawl to hold it out of engagement with the ratchet wheel, a cam follower connected to said member to actuate the same but shiftable relatively thereto, and manually operated means for shifting said follower into engagement with any one of said selecting cams.

16. A sewing machine attachment comprising a frame, a lever pivoted to the frame for oscillating movement, a presser foot carried by the lever, means to oscillate said lever comprising a cooperating pawl and ratchet wheel, a fork arm oscillatably mounted on the frame and connected to said pawl to effect step-by-step rotation of the ratchet wheel, a plurality of selecting cams rotatably mounted on the frame, means for rotating said cams in a step-by-step movement by oscillation of said fork arm, a member movably mounted on the frame and adapted to engage said pawl to hold it out of engagement with the ratchet wheel, a cam follower connected to said member to actuate the same but shiftable relatively thereto, manually operated means for shifting said follower to place it into engagement with one of said selecting cams, and means for moving said follower out of engagement with the selecting cams upon initial movement of said manually operated means.
